H. H. SOUTHWORTH.
DEVICE FOR SUPPLYING COOLING WATER.
APPLICATION FILED JAN. 15, 1913.

1,139,461.

Patented May 11, 1915.

UNITED STATES PATENT OFFICE.

HARRISON H. SOUTHWORTH, OF CLEVELAND, OHIO, ASSIGNOR, BY MESNE ASSIGNMENTS, TO THE ICELESS MACHINE COMPANY, OF CLEVELAND, OHIO, A CORPORATION OF OHIO.

DEVICE FOR SUPPLYING COOLING-WATER.

1,139,461.

Specification of Letters Patent. Patented May 11, 1915.

Application filed January 15, 1913. Serial No. 742,097.

To all whom it may concern:

Be it known that I, HARRISON H. SOUTHWORTH, a citizen of the United States, and a resident of Cleveland, in the county of Cuyahoga and State of Ohio, have invented certain new and useful Improvements in Devices for Supplying Cooling-Water; and I do hereby declare that the following is a full, clear, and exact description thereof, reference being had to the accompanying drawings, and to the letters of reference marked thereon, which form a part of this specification.

This invention relates to improvements in devices for supplying cooling water for use with refrigerating apparatus and consists of the matters hereinafter described and more particularly pointed out in the appended claims.

20 In the drawings:—Figure 1 is a view representing a rear end elevation, partially broken away, of a refrigerating apparatus, provided with my improved means for supplying cooling water. Fig. 2 is a view representing, on an enlarged scale, a vertical central section illustrating the novel features of my improvement. Fig. 3 is a vertical cross section on a reduced scale of the upper part of the apparatus shown in Fig. 1.

30 The invention is shown herein as applied to a refrigerating apparatus of the absorption type, in which are provided two generator-absorbers which alternately act as generators and as absorbers, substantially as described in the application filed by Harrison H. Southworth and Fred W. Wolf, Serial No. 727,353, filed October 23rd, 1912. It will be understood however that the invention is not limited in its application to this 40 type of apparatus but may be applied to any apparatus requiring the use of cooling water in its operation.

Referring now to the drawings, 10, 10 indicate the two generator-absorbers which 45 are supported above an elongated tank 11 in which is contained the liquid condenser and receiver coil 12. 13 indicates a water discharge nozzle adapted to be shifted to discharge the cooling water on either of the 50 drums 10. 14 indicates the burner which is capable of shifting movement between the two drums and is adapted to heat one or the other as the case may be. The water discharged through the nozzle 13, after it

leaves the particular drum to which it is 55 being supplied, falls into the tank 11 in which it accumulates so as to cover the liquid condenser and receiver coil 12, the level of the water in said tank being determined by an overflow pipe 15. 60

The water from the nozzle 13, if supplied directly from a source of water supply at the usual temperature of such water, will not in its passage over the hot generator-absorber drum cool it, nor in its cooling 65 effect upon the receiver and condenser coil 12 acquire all of the heat units which it is capable of taking up and will usually be still cold enough to be efficiently used again as a cooling agent for the generator-absorber and condenser. The object of the 70 present invention is to provide a device by means of which the cooling water in the tank 11 may be mixed with the fresh incoming stream of cooling water in automatically varying proportions depending upon the temperature of the water in the tank so as to economize the use of the water from the source of supply. The advantage 75 of such a device will be realized when it is 80 remembered that one of the two main sources of expense involved in the operation of a refrigerating apparatus is the cost of the cooling water.

In carrying out my invention as herein 85 described, I provide a valve mechanism in conjunction with an aspirating device which is adapted to draw up with the stream of fresh water from the source of supply, a certain proportion of the water in the cooling 90 tank, the valve mechanism which controls the size of the stream of fresh water depending for its operation upon the temperature of the water in the tank.

Referring now to that embodiment of my 95 invention illustrated in the drawings, 16 indicates a pipe which is connected at its upper end with the oscillating discharge nozzle 13, and depends at its lower end into the body of water contained in the tank 11. 100 17 indicates a casing connected to the lower end of said pipe 16, and preferably located near the bottom of the tank where the water is coldest. Said casing has at its lower end a valve chamber 18 and a passage 19 opening laterally from said chamber. 20 indicates a pipe connected with the casing and communicating with said passage 19, said

pipe leading from a source of cooling water supply and being adapted to direct a stream of water into the valve chamber under a head or pressure.

- 5 Within the casing and communicating with the upper side of the valve chamber 18 is formed a nozzle 22, which is provided at its lower end with a conical valve seat 23. 24 indicates a needle-valve adapted to co-act 10 with the seat 23 and having a stem 25 which projects downwardly through the lower end of the casing. Said lower end is closed by a suitable stuffing box 26, in which the valve-stem has reciprocating bearing.
- 15 Openings or ports 27 are formed in the casing wall about the nozzle 22 in such manner that when a stream of water is discharged through the nozzle, the water surrounding the casing will be sucked or 20 drawn into the casing and will be carried with said stream up through the pipe 16. Apparently the amount of water drawn in from about the casing will depend upon the size of and resulting velocity of flow 25 of the stream discharged through the nozzle, so that the proportion of water taken from the tank may be varied to increase or diminish it, by increasing or diminishing the distance of the valve 24 from its seat 30 23, thus increasing the size of the stream passing through the nozzle and proportionately diminishing its speed or vice versa.
- Clearly the proportion of cooling water 35 from the tank to be mixed with the fresh incoming stream from the source of supply, must be less when the water in the cooling tank is warm than when it is cold, and therefore I provide in connection with the valve a thermostatic device for controlling 40 the opening and closing movement thereof which depends for its operation upon the temperature of the water in the tank. As a most convenient and efficient device of the kind in the case of a refrigerating apparatus of the absorption type, I make use 45 of the condensing and receiving coil itself. Apparently the pressure therein will vary with the temperature of the water surrounding it.
- 50 I provide a casing 28 connected by a pipe 29 with the condensing coil and containing a diaphragm 30 which is subjected to the pressure in said condenser. 31 indicates a stem arranged to be actuated by the movement of the diaphragm under the pressure 55 of said condenser. These parts may be of any familiar or desired construction.
- 32 indicates a lever fulcrumed to a lug 33 fixed to the casing on one side of the 60 stem 31 and at its other end having pivotal connection with the lower end of the valve stem 25.
- 34 indicates a fixed bar having a depending arm 35 the lower end of which is adapted to act as a stop to limit the upward

movement of the lever 32. A set-screw 36 threaded through the lever is adapted to engage at its end against the stop-arm 35, said set-screw providing means for adjusting the engaging part of the arm relatively to the stop. 38 indicates a coiled spring the tension of which is carefully predetermined and which connects the lever 32 with the fixed bar 34. As shown, the said spring is connected to the bar 34 by a bolt 37 and nuts 39 for purposes of adjusting the tension.

The operation of the device is apparent from the above description. The stream of fresh water from the supply pipe 20 80 discharges through the nozzle 22 into the pipe 16 leading to the discharge pipe 13. Water from the tank is drawn with said stream through the openings 27 in the casing. When the water in the tank surrounding the condenser is cold there is a corresponding pressure in the condenser acting upon the diaphragm 30 which, being insufficient to overcome the tension of the spring 38, allows the valve to stand at a 90 minimum distance from its seat, thus causing a small stream at high velocity to pass through the nozzle 22 so as to draw in with said stream a large proportion of water from the tank. As the temperature of the 95 water in the tank increases, the pressure in the condenser and upon the diaphragm 30 increases in proportion and causes a proportionate enlargement of the valve opening. This permits a larger stream of fresh 100 water at slower speed to be discharged through the nozzle 22 with the result that a smaller proportion of water from the tank is drawn in with said stream.

The stop 35 prevents a complete closing 105 of the valve on its seat so that a minimum discharge of fresh water is always discharged through the nozzle 22, this being necessary in order to produce the required indrawing of water from the tank at all 110 times.

I claim as my invention:—

1. The combination of a member to be cooled, means for supplying cooling water to such member, a receptacle for receiving the water flowing from such member, means for mixing used water with fresh water and directing the same to the member to be cooled, and means responsive to the temperature of the water in the receptacle for controlling the proportions of the mixture.

2. A device for supplying cooling water, comprising in combination with a receptacle to receive the water, and a main water supply pipe, an auxiliary supply pipe depending into said receptacle below the water level therein, an aspirating device interposed between said two pipes, a valve for controlling the flow through said aspirating device, said valve having limited movement toward its 120 125 130

seat, and thermostatic means located in said tank for controlling said valve.

3. A device for supplying cooling water, comprising in combination with a receptacle to receive the water, and a main supply pipe, an auxiliary supply pipe depending into said receptacle below the water level therein, a casing connected to said auxiliary pipe, a nozzle located within said casing adapted to discharge into said auxiliary supply pipe, the casing being provided with inlet openings about said nozzle and with a valve chamber opening into the inlet end of said nozzle, means connecting said main supply pipe with said valve chamber, a valve controlling the flow from the main supply pipe to said nozzle, means tending to normally close said valve, a stop limiting the movement of said valve toward its seat, a diaphragm chamber connected with said condenser, a diaphragm in said chamber, and means intermediate said diaphragm and said valve closing means acting to open said valve with the expansion movement of said diaphragm. 70

10 to discharge into said auxiliary supply pipe, the casing being provided with inlet openings about said nozzle and with a valve chamber opening into the inlet end of said nozzle, means connecting said main supply pipe with said valve chamber, a valve controlling the flow from the main supply pipe to said nozzle, means limiting the movement of the valve toward its seat, and a thermostatic device located in said receptacle and 15 operatively connected with said valve to control its movement.

4. In a refrigerating apparatus, in combination with a generator absorber, a device for discharging cooling water on said generator-absorber, a water tank containing said condenser and arranged to receive the cooling water after it leaves said generator-absorber, a main water supply pipe adapted to direct water to said discharging device, 20 means for forcing water from the tank with the water from the main supply pipe, and thermostatic means acting to automatically determine the proportions of water from the main supply pipe and from the tank directed 25 to said discharging device.

5. In a refrigerating apparatus, in combination with a generator-absorber, a device for discharging cooling water on said generator-absorber, a water tank containing said condenser and arranged to receive the cooling water after it leaves said generator-absorber, a main water supply pipe adapted to direct water to said discharging device, means for mixing water from said tank with 30 the water from the main supply pipe and forcing the same to the discharging device, a diaphragm chamber connected with said condenser, a diaphragm located therein, and means actuated by said diaphragm for determining the proportions of water from the main supply pipe and from the tank directed 35 to said discharging device.

6. In a refrigerating apparatus in combination with the condenser and a cooling water tank containing said condenser, a main water supply pipe, an auxiliary supply pipe for supplying cooling water for use in the apparatus, said auxiliary pipe depending into the tank below the water level 40 therein, a casing connected to the lower end of said auxiliary pipe, a nozzle located within said casing adapted to discharge into said auxiliary pipe, the casing being provided with inlet openings about said nozzle, and 45 with a valve chamber opening into the inlet end of said nozzle, means connecting said main supply pipe with said valve chamber, a valve controlling the flow from the main supply pipe to said nozzle, means tending to normally close said valve, a stop limiting the movement of said valve toward its seat, a diaphragm chamber connected with said condenser, a diaphragm in said chamber, and means intermediate said diaphragm and said valve closing means acting to open said valve with the expansion movement of said diaphragm. 70

7. In a refrigerating apparatus, the combination with a generator-absorber, of a device for directing cooling water to the generator-absorber, a receptacle adapted to receive water from the generator-absorber, means for mixing the same with fresh water, means for taking water from the receptacle for re-using, and a pressure-responsive device affected by the temperature of the water within the receptacle to control the proportions of the mixture of water from the receptacle and fresh water.

8. In a refrigerating apparatus, in combination with a generator-absorber, a device for discharging cooling water on said generator-absorber, a water-tank adapted to receive said water from said generator-absorber, a condenser within the tank, a main water supply pipe adapted to direct water to said discharging device, means for forcing water from the tank to be reused in said discharging device, and means acting to automatically increase the water from the main water supply as the pressure in the condenser approaches a predetermined point.

9. In an absorption refrigeration apparatus, the combination, with the still and condenser, of a tank for receiving cooling liquid from the still, means for supplying fresh water, means for discharging water onto the still taken partly from the tank supply and partly from the fresh water supply, means controlling the last named means affected by the temperature of the used liquid in the tank.

10. In an absorption refrigeration apparatus, the combination, with the still and condenser, of a tank for receiving cooling liquid from the still, means for supplying fresh water, means for discharging water onto the still taken partly from the tank supply and partly from the fresh water supply, and automatic means affected by the temperature of the water in the tank for regulating the ratio between such supplies to produce a substantially constant temperature of water discharged on the still.

11. In an absorption refrigeration apparatus, the combination, with a still and condenser, of a tank for liquid, a conduit for directing liquid onto the still from which it passes to said tank, and means controlled by

conditions in the condenser for returning some of the same liquid with an admixture of fresh liquid onto the still.

12. In an absorption refrigeration apparatus, the combination, with a still and condenser, of a tank for liquid, a conduit for directing liquid onto the still from which it passes to said tank, means for returning some of the same liquid with an admixture of fresh liquid onto the still, and an automatic device affected by the temperature of the used liquid for regulating the proportion

between the fresh and used liquid to give a substantially even temperature to the mixture.

15 In testimony that I claim the foregoing as my invention I affix my signature in the presence of two witnesses, this third day of January A. D. 1913.

HARRISON H. SOUTHWORTH.
